CONCRETE ROAD FORM

Filed Nov. 10, 1927

Inventor

Frank G. Ginetzki

By Clarence O'Brien, Attorney

UNITED STATES PATENT OFFICE.

FRANK GAETANO GINNETTI, OF WILLIMANTIC, CONNECTICUT.

CONCRETE-ROAD FORM.

Application filed November 10, 1927. Serial No. 232,368.

My invention relates to improvements in concrete road forms wherein the same is especially constructed for use as a form in the construction of concrete highways, and 5 upon which the conventional road surfacing machines employed for surfacing the concrete, during the forming of the road is mountable for movement.

The paramount purpose of the mold is to 10 provide such a novel mold which can be readily reversed for use, which eliminates the necessity of employing more than one design of same.

A very important object of my invention 15 is to provide a mold which may be readily reversed, and which when properly set in position, may be securely fixed to the earth.

Another object resides in the means whereby a plurality of such novel mold sections 20 may be conveniently jointed end to end.

Other very novel objects and advantages 25 of my novel form will become apparent as the same is better understood from the specification and claims to follow.

25 In the drawing:—

Figure 1 is a top plan view of the mold section showing the same unsecured to the earth.

Fig. 2 is an end elevation of the mold as 30 represented in Fig. 1, showing the same in secured relation with the earth.

Fig. 3 is a top plan view of the plate member upon which the stake holder is pivotally associated.

35 Fig. 4 is a side elevation of the same, and

Fig. 5 is a perspective view of the member employed for connecting the sections together.

Now for a more detail description of my 40 invention, I refer to the drawings, in which like numerals designate like parts. In the operation of forming the concrete road, I employ a multiplicity of my improved concrete road forming section, however, it is 45 sufficient to describe one single section, due to the fact that the sections are identical in construction.

The section includes an elongated plate 1, which is bent to a right angular shape in 50 cross section, as is clearly shown in Fig. 2 of the drawings. One longitudinal edge portion is bent inwardly to provide a flange 2, while the opposite longitudinal edge portion is U-shaped as at 3, and an elongated web 4 has one longitudinal edge portion bent

obliquely and at 5 to flushly engage the underside of the flange 2, while the opposite longitudinal edge portion of the web is opposingly bent obliquely so that the same will engage flushedly in relation with the under 60 side of the free leg of the U-shaped portion 3.

At one edge portion of the web a longitudinal slot 6 is formed, while at spaced intervals, in the web, transverse openings 7 are 65 formed.

An angle member 8 is secured to the plate 1, and is provided with an upstanding block member 9, having an opening 10 substantially through the center thereof. One corner 70 portion of this block is shaped to provide a flat surface 11 in substantially parallel relation with the base portion of the angle member 8.

At this surface 11, a recess 12, is formed 75 in substantially right angular relation to said surface. The adjacent corner of the block 9 is also formed to provide a flat surface 13 having formed therein, a recess 14 extending substantially in horizontal relation to the 80 base of said angle member. The block is provided with a portion 15, which when the angle member 8 is secured in place in relation to the plate 1, will engage in the portion 3 of the said plate.

The outer portion of the block 9 is adapted to protrude through the transverse opening 7 in the web 4, when the angle member 8 has been properly positioned and secured directly underlying one of the respective 90 transverse openings.

A bolt 16 is secured through the opening 10 for pivotally mounting the free end of a U-shaped element 17. Inwardly from the right portion, and at opposed portions in the 95 right leg members thereof, a pair of elongated openings 18 are formed, which are adapted to receive the tapering body of a wedge 19. In positioning the U-shaped member 17, in the manner clearly shown in Fig. 2, the pair 100 of elongated openings 18 will be in registry with the recess 14 in the block 9, so that when the wedge 19 is formed through the opening 18, the same will be disposed in meshed relation with said block.

At one end of each form section, a substantially triangular-shaped connector 20 is 105 adapted for slidable disposition therein. The connector is constructed of a single strip of material, of proper width, while the cross

section of the same is substantially triangular. One end portion of the strip is slit longitudinally to provide an underlying tongue 25, adapted to engage under the opposed end of the grip.

Each end of the strip is provided with a laterally projecting member, which members are brought together and riveted to provide an upstanding lug for the connector, 10 and which is slidable within the slot 6 of the web, whereby the same may be shifted back and forth therein, for either engaging or disengaging the connector with respect to the ends portion of an adjacent section.

15 As is clearly shown in Fig. 2 of the drawings, the plate 1 is right angular in cross section, so that the same is provided with a pair of flat supporting surfaces. Upon either one of these flat surfaces, the section 20 may be supported, and in respect to which ever one of the surfaces the section is supported, the U-shaped member 17 is released by the disengagement of the wedge 19, so that the opening 18 therein may register with 25 the proper opening, so that a stake 27 may be inserted through the U-shaped member 17, adjacent the bight portion thereof, and driven into the earth.

30 This securing means is provided whereby the sections may be projected in proper relation with respect to the concrete material, and upon the latch portion 2, or U-shaped portion 3 as the instance may be, a concrete smoothing apparatus is movable.

35 It will be seen that I have provided a novel concrete mold for forming concrete roadways, and which is reversible in use, thus eliminating the necessity of providing more than one design of mold section.

40 While I have illustrated the preferred embodiment of my novel form, I do not wish to limit myself to this particular construction, and slight changes may be made therein for more perfect adapting the same, with-

out departing from the spirit and scope of 45 the invention.

Having thus described my invention, what I claim as new is:—

1. In a concrete road form, an elongated angle plate, and means on said plate whereby the plate may be supported on either surface thereof in secured relation with the ground.

2. In a concrete road form, an elongated angle plate, a pivotal member on said plate, 50 and an element adapted to be received by said pivotal member for securing said angle plate to the ground, and upon either of the surfaces thereof.

3. In a concrete road form, an elongated angle plate, a web connecting the longitudinal edges thereof, said web being formed with an opening therein, a construction protruding through said opening, a pivotal member on said construction, means for adjusting said pivotal member in one fixed position to the second position at right angles to the first position, and an element adapted to be received within said pivotal member, 60 whereby the said plate may be secured to the ground upon either of its right angular surfaces.

4. In a concrete mold, an elongated angle plate, a web connecting the longitudinal edges thereof, an outstanding construction 75 associated with said web, said outstanding construction being formed with elongated openings extending inwardly at right angles to each other and in parallel relation to the adjacent surface of the angle plate, a pivotal member on said construction, means for adjusting said member to a fixed position with respect to one of said openings, and an element adapted to be driven into the ground in secured relation with said pivotal member. 80

85 In testimony whereof I affix my signature.

FRANK GAETANO GINNETTI.
